CARRYING SCRAPER

John J. Low, Los Angeles, Calif., assignor to Kay-Brunner Steel Products, Inc., a corporation of Delaware

Application February 1, 1939, Serial No. 254,021

7 Claims. (Cl. 37—126)

My invention relates to carrying scrapers of the character embodied in my co-pending application Serial No. 217,658, filed July 6, 1938, wherein is embodied a bowl, an apron at the front of the bowl, an ejector for ejecting earth from the bowl, and a mechanism operatively connecting the ejector to the apron by which actuation of the ejector is effected in such manner that its movement from a retracted position at the top of the bowl to an advanced position at the front of the bowl in ejecting earth therefrom, is initiated only after the apron has reached such an open position with respect to the bowl that it does not obstruct or interfere with discharge of earth from the bowl by the ejector.

It is a purpose of my present invention to provide a carrying scraper embodying a mechanism for actuating the ejector which functions to apply to the ejector a force sufficient to move the earth in a fully loaded bowl for initiating discharge of the earth therefrom; to decrease the applied force as the load is decreased by reason of its discharge; and to increase the rate of travel of the ejector as the applied force is decreased so as to so accelerate movement of the ejector that a final throwing of the remaining earth from the bowl is effected. By operating the ejector in this manner a more rapid and complete discharge of earth from the bowl is secured and without the parts of the mechanism being subjected to any undue stresses or strains, and through the application of a minimum pull on the cable or other medium for operating the mechanism.

It is also a purpose of my invention to provide a carrying scraper embodying a mechanism for operating the earth ejector in the manner above described and which is devoid of springs or any other devices that may complicate and weaken the structural simplicity and ruggedness by which my mechanism is in part characterized.

I will describe only one form of carrying scraper embodying my invention and will then point out the novel features in claims.

Figure 1 is a view showing in top plan one form of carrying scraper embodying my invention.

Fig. 2 is a view showing the carrying scraper in side elevation and earth scraping position.

Fig. 3 is a view similar to Fig. 2, but partly in vertical section and with the bowl in earth carrying position.

In carrying out my invention, I provide a main frame A having inclined side beams 15, 15 connected at their forward ends by a cross beam 16 having a forward extension 17 from which

depends a standard 18 supporting a swivel wheel truck 19 having a draw bar 20 adapted for connection to a tractor.

A second frame B is pivoted on the frame A between the side beams 15 for movement about a transverse and horizontal axis. This frame B comprises an upper rigid structure having upper side beams 21, 21 and a rear cross beam 22. Rear and front corner beams 23, 23 and 24, 24 depend from the side beams 21. These corner beams are rigidly connected to the side beams and to each other by lower side beams 25, 25.

The rear ends of the beams 25 are rigidly connected by a cross beam 26, while to the beams 22 and 26 rigid frames 27 and 28, respectively, are secured to coact with an axle 29 and wheels 30 in forming a rear wheel truck for the scraper.

An axle 31 is mounted in and extends through the frames 27 and 28, while on the ends of the axle the rear ends of beams 15 are pivoted to allow vertical movement of the frame B relative to the frame A and about the axle 31 as a center. The frame B has secured therein a bowl C which includes a pair of side plates 32 between which is secured a combined bottom and back end plate 33 which is curved about an axis E and terminates at its forward end in a blade 34.

For actuating the frame B to lift the bowl C from scraping position to carrying position the following mechanism may be provided. A pair of turn-buckles 35 are secured to the corner beams 23 and to a pair of rods 36, with the latter in turn pivotally connected to a pair of arms 37 fixed to the opposite ends of a shaft 38 journaled in bearings 39 secured to the cross beam 16. Fixed to the shaft 38 at a point between those bearings 39 at the center of the shaft, are a pair of relatively long arms 40 disposed substantially at right angles to the shorter arms 37. Sheaves 41 are mounted between the free ends of the arms 40, while a companion set of sheaves 42 are supported on a shaft 43 carried by a block 43a secured on the extension 17. A cable 44 is extended around both sets of sheaves 41 and 42 and secured at one end to one set of sheaves or the other. The other end of the cable is extended downwardly at the upper side of the standard 18 and beneath a sheave 45 on a shaft 46, for connection to a tractor.

From the preceding description it will be clear that by pulling on the cable 44 the arms 40 are rocked forwardly to rotate the shaft 38 and thus lift the arms 37 to elevate the rods 36, thereby elevating the front end of the frame B to raise the bowl C.

For retaining earth in the bowl C after loading thereof, an apron D is provided which includes a pair of upwardly extending side beams 47 to which are secured downwardly extending arms 47a pivoted on trunnions 48 secured to the beams 21 so that the apron is movable between the sides of the frame B to occupy open and closed positions with respect to the bowl.

The mechanism for lifting the apron D comprises a set of sheaves 49 carried in a block 50 secured to the apron, and another set of sheaves 51 carried on a cross beam 52 secured to the forward ends of the side beams 21 by upstanding beams 53. A cable 54 is extended around the two sets of sheaves with one end secured to the sheaves 49 and the other end extended forwardly over a sheave 55 on the shaft 43. From this point the cable proceeds downwardly beneath a sheave 56 on the shaft 46, from which it leads to the tractor. Manifestly, the cable 54 is operable to lift the sheaves 49 thereby swinging the apron D upwardly about the trunnions 48 as a center.

For discharging all earth from the bowl after the apron has been moved to an unobstructed position, an ejector F is provided. This ejector comprises side arms 57 bridged at their rear ends by a blade 58 from which rises an inclined plate 59 spanning the arms and secured to a frame comprising side bars 60 bolted to the side arms, and vertical bars 61 secured to the side bars and connected at their upper ends by a cross bar 62. In the operation of the ejector the blade 58 cuts the earth free of the bowl plate 33, while the plate 59 pushes the earth forwardly and away from the plate 33 so that it cannot pack and interfere with the proper operation of the ejector in its earth ejecting movement.

The forward ends of the arms 57 are provided with trunnions 63 journaled in bearings 64 fixed to the beams 21. These trunnions constitute the axis E about which the ejector F swings, with the blade 58 maintaining a position parallel to the bowl plate 33.

For operating the ejector, the elevating motion of the apron is utilized through a mechanism which comprises two sets of links situated at opposite sides of the bowl, and as they are identical in construction, a description of one will suffice for both.

A two part bracket 69 rises from the side beam 21 and in which the upper end of a lever 70 is pivotally mounted by means of a pin 71. To the forward end of the lever the upper end of a link 72 is pivotally connected by a pin 73, the lower end of the link being pivotally connected by a pin 74 to the forward end of a downwardly curved extension 75 of the respective ejector arm 57. This extension 75 in effect forms a crank. The upper end of the respective apron beam 47 is operatively connected to the lever 70 by a link 76, pins 77 and 78 being provided for the purpose.

To brace the apron beams 47, 47 and provide a substantial mounting for the pins 71, 71, a tubular beam 79 extends between the apron beams and is provided with upstanding ears 80, 80 in which the inner ends of the pins 77 are mounted.

The operation of the ejector actuating mechanism will be understood from a consideration of Fig. 3. With the apron in closed position as shown in solid lines, the ejector occupies retracted position at the top of the bowl, while the two sets of links comprising the ejector actuating mechanism are in the solid line positions shown. Upon lifting the apron to the dot and dash line 75

position through operation of the cable 54, the pivots 71 are moved upwardly and rearward about the pivots 48 as a center. Under this motion the links 76 are swung upwardly about the pivots 78 to the position shown in dot and dash lines, there being no appreciable movement of the levers 70, and hence no appreciable movement of the ejector. Thus, the apron can be opened to the dot and dash line position without movement of the ejector thereby permitting that earth which is free to gravitate from the bowl and apron to do so.

By now elevating the apron to the dash line position, which is the full open position thereof, the links 76 now exert a lift on the levers 70 moving them to the dash line position and thereby pulling the links 72 upwardly to the dash line position. Under this elevating movement of the links 72 the arms 57 are swung downwardly about the axis E as a center thereby advancing the ejector downwardly and forwardly in the bowl.

By reason of the relation of the pivots of the links, arms and levers to each other the effective leverage of the links 75 is greatest during the first part of their movement upwardly from the dot and dash line position, such leverage decreasing as the links approach their uppermost position. This leverage being at all times transmitted to the ejector through the links 72 and the cranks 75, it becomes apparent that the power or moving force applied to the ejector by the mechanism, is greatest at the beginning of its movement from retracted position, decreasing continuously until the ejector reaches its advanced position. It will be apparent, also, that as the effective leverage decreases the rate of movement of the ejector increases, and thus through my mechanism motion of the ejector from retracted to advanced position is accelerated. The design of my mechanism is such that for substantially half of the forward movement of the ejector the effective leverage and, hence, the applied power, is at substantially a constant maximum. Therefore, the rate of movement of the ejector must be of necessity, substantially constant. Beyond this half-way point the effective leverage decreases rapidly thereby decreasing the power applied accordingly, but rapidly increasing the rate of movement of the ejector.

In actual practice, the advantages provided by my mechanism will be apparent from the following. Assuming that the apron has just been moved to the open position shown in dot and dash lines in Fig. 3 and the loaded bowl tilted, a certain part of the earth will gravitate from the bowl. Continued opening of the apron at a constant rate of movement now sets the ejector actuating mechanism into operation causing the ejector to move relatively slowly and at substantially a constant rate. It is during this period of movement that the maximum effective leverage and hence the maximum power of which the mechanism is capable, is applied to the ejector. As it is at this time that the earth load is the greatest, the mechanism moves the ejector with a force sufficient to pull that maximum load forwardly in the bowl.

As the earth advances it is discharged from the bowl lessening the load and hence the resistance offered to movement of the ejector. Meanwhile, the mechanism is functioning to decrease the power or force applied to the ejector and to a de-

gree corresponding substantially to the decrease in load.

Inasmuch as the speed of travel of the ejector increases as the power applied decreases, movement of the ejector is accelerated to such an extent that in the final part of its movement the earth remaining in the bowl is projected or thrown from the bowl. Thus, in the final advanced position of the ejector all earth has been swept from the bowl.

From this mode of operation of the ejector it becomes manifest that according as the earth load in the bowl decreases the power applied to the ejector decreases, while the rate of movement of the ejector increases.

Upon returning the apron to closed position or to partly open position for scraping as shown in Fig. 2, reverse movements of the link mechanism occurs to return the ejector to retracted position at the top of the bowl.

Although I have herein shown and described only one form of carrying scraper embodying my invention, it is to be understood that various changes and modifications may be made herein without departing from the spirit of my invention and the spirit and scope of the appended claims.

I claim:

1. A scraper, comprising; a bowl; an apron having rearwardly extending arms pivoted on the bowl; an ejector having arms pivoted on the bowl to swing about an axis; cranks on the ejector arms projecting forwardly from said axis; levers pivoted on the bowl above the cranks; links connecting the forward ends of the levers to said cranks; and other links connecting the apron to the levers at a point in the rear of the connection of the levers with the first mentioned links.

2. A scraper, comprising; a bowl; an apron at the front of the bowl movable to occupy open and closed positions with respect to the bowl; an ejector movable in the bowl to or from a retracted position at the top of the bowl to or from an advanced position at the front of the bowl; and a mechanism operatively connecting the apron and ejector for advancing or retracting the ejector according as the apron is open or closed, said mechanism including at least one set of elements each set comprising a lever mounted on the bowl, a link connecting one side of the ejector to the lever, and a second link connecting the corresponding side of the apron to the lever at a point between the first mentioned link and the lever.

3. In a carrying scraper; a bowl having a circularly curved back and bottom wall; arms pivoted on the bowl substantially at the center of

curvature of said bowl wall; an earth ejector carried by said arms to swing forwardly through the bowl; an apron pivoted on the bowl to swing about an axis spaced from the pivotal axis of the arms; levers pivoted to the bowl; links pivoted to the arms and to the levers; other links pivoted to the apron and to the levers; and means for moving the apron, whereby the levers and links coact to move the ejector forwardly at a progressively increasing speed.

4. In a carrying scraper; a bowl; arms pivoted on the bowl; an earth ejector carried by said arms to swing forwardly through the bowl; an apron pivoted on the bowl; levers pivoted to the bowl; links pivoted to the arms and to the levers; other links pivoted to the apron and to the levers; and means for moving the apron, whereby the levers and links coact to swing the ejector forwardly through the bowl.

5. In a carrying scraper; a bowl; arms pivoted on the bowl; an earth ejector carried by said arms to swing forwardly through the bowl; an apron pivoted on the bowl; levers pivoted to the bowl; links pivoted to the arms and to the levers; other links pivoted to the apron and to the levers than the pivots of the first mentioned links; and means for moving the apron, whereby the levers and links coact to actuate the ejector.

6. In a carrying scraper; a bowl; arms pivoted on the bowl; an earth ejector carried by said arms to swing forwardly through the bowl; an apron pivoted on the bowl; links pivoted to the arms at points forwardly of the arm pivots; levers pivoted to the bowl above and rearwardly of the arm pivots, and to the links; other links pivoted to apron and to the levers between the lever pivots and the pivots of the first mentioned links to the levers; and means for moving the apron whereby the levers and links coact to swing the ejector forwardly through the bowl at a progressively increasing speed.

7. In a carrying scraper; a bowl; arms pivoted on the bowl; an earth ejector carried by said arms to swing forwardly through the bowl; an apron pivoted on the bowl; levers pivoted to the bowl above and rearwardly of the arm pivots; links pivoted to the arms forwardly of the arm pivots and pivoted to the levers; other links pivoted to the apron and to the levers between the lever pivots and the pivots of the first mentioned links; and means for lifting the apron to open position in respect to the bowl, whereby the levers and links coact to swing the ejector forwardly through the bowl at a progressively increasing speed after the apron has been lifted to a predetermined open position.

JOHN J. LOW.
